SHIPPING CONTAINER CONSTRUCTION

Orville M. Masters and Henry G. Stager,
Syracuse, N. Y.

Application July 12, 1935, Serial No. 31,079

6 Claims. (Cl. 229—14)

Our invention relates to shipping containers and more particularly to a new and improved means for protecting the object to be shipped when packed, and a method of making such means.

In the shipping containers of the prior art used for packing for shipment radios, refrigerators and other heavy or bulky articles which are likely to be damaged in transit, it has been customary to enclose the object to be shipped in a solid walled container of wood or paper board and space it from the side walls of the container by various means such as straw, paper board, etc. When paper board is used it has been found just as satisfactory and much more economical, instead of a complete lining of paper board, merely to provide corner members of paper board to keep the radio or other article spaced from the side walls of the shipping container. Such corner spacing devices or pads have hitherto been made up of single units of paper board folded at the midpoint with the several units pasted together to form a corner unit of a plurality of thicknesses or ply of paper board. Such a corner structure, made of corrugated paper board, is shown in Agar Patent No. 1,613,152 issued January 4, 1927.

While the construction shown in the Agar patent has been found fairly satisfactory as far as protecting the article being shipped is concerned, it is quite expensive to manufacture and an object of our invention is therefore to provide a shipping container which is more economical to manufacture and which at the same time serves more effectively to protect the article from shocks and damage in transit.

Another object of our invention is the provision of a shipping container having reinforcement means or pads at the corners thereof which engage the corners of the object to be shipped to space it from the side walls of the container and protect it from damage during shipment.

Our invention further contemplates the provision of a protective corner padding structure each of which as used in the container is made up of a single unit of paper board scored and folded to form a protective corner pad having a plurality of ply of paper board at each side of the corner.

Still another object of our invention is the provision of a skeleton lining for a shipping container comprising a plurality of ply of paper board which may be used without pasting it into the enveloping container and without the necessity of glueing the individual ply to each other.

Our invention further contemplates the provision of a unitary top and bottom or end pad

structure adapted to be used in a shipping container for protecting the top or bottom of the object to be shipped, such top or bottom padding being part of a skeleton lining for the enveloping container and each being formed of a single unit of paper board scored and folded to form a single angular four sided skeleton enclosure for protecting the perimeter of the top or bottom of the object to be shipped.

Our invention further contemplates the provision of a method of forming the individual padding and spacing units for a shipping container whereby a complete skeleton lining for the container may be formed quickly and cheaply.

More specifically our invention has for an object the provision of a method of forming the individual corner pads for the sides, top and bottom of a skeleton padding and spacing structure to be used in a shipping container in which the individual pads are formed of a single unit of paper board scored, slit and folded into a unitary corner construction.

Other objects and advantages of our invention will be more apparent from the following specification when taken in conjunction with the accompanying drawings in which:

Figure 1 is a perspective view showing a protective corner pad for use in a shipping container made of single wall double faced corrugated paper board.

Figure 2 is a perspective view of the protective corner pad of Figure 1 prior to folding and showing the manner of scoring and sectionalizing the pad unit.

Figure 3 is a view similar to Figure 1 showing a protective corner pad made up of single wall double faced corrugated paper board in which the number of ply on each side of the corner is increased over that shown in Figure 1.

Figure 4 is a view similar to Figure 2 showing the manner of scoring and sectionalizing double wall corrugated paper board to form a protective corner pad structure.

Figure 5 is a perspective view showing the construction illustrated in Figure 4 in folded condition.

Figure 6 is a perspective view similar to Figure 1 in which triple wall corrugated paper board is used.

Figure 7 is a perspective view illustrating the complete shipping container with the skeleton protective corner pad structure partially removed to illustrate its construction.

Figure 8 is a perspective view showing the pro-

protective skeleton corner pad structure illustrated in Figure 7.

Figure 9 is a view taken on the line 9—9 of Figure 8.

Figure 10 is a perspective view showing single wall double faced corrugated paper board scored and sectionalized to form the top or bottom sections of the protective skeleton padding.

Figure 11 is a perspective view showing the structure of Figure 10 folded on the sectionalizing lines.

Figure 12 is a perspective view showing the structure of Figures 10 and 11 and illustrating the manner of folding the pad on the scoring lines to form one corner of the top or bottom units of the skeleton padding.

Figure 13 is a perspective view of the structure of Figures 10, 11 and 12, showing a portion of the top or bottom units of the skeleton padding in completely folded condition.

Figure 14 is a view similar to Figure 9 showing a modified construction employing single wall corrugated paper board for forming the top or bottom units of the skeleton padding.

Figure 15 is a perspective view of the structure of Figure 14 in unfolded condition.

Figure 16 is a perspective view showing a machine suitable for scoring and sectionalizing the paper board for forming the pad structures illustrated in Figures 1 to 15 inclusive.

Figure 17 is a view showing a machine suitable for use for forming the top and bottom sections of the skeleton corrugated paper board structure.

While the protective skeleton padding of our invention may be made of various materials, such as those known in the art to which this invention applies as solid fibre, pasted chip board, box board with a liner and in general may be made of any board having a liner and a filler, it is preferably made of corrugated paper board. We have found that padding and spacing units for use in a shipping container made of single wall double faced corrugated paper board are very effective to protect articles being shipped due to the resilient and yet firm and rigid characteristics of that type of paper board.

In Figures 1 and 2 we have illustrated a unit of single wall double faced corrugated paper board comprising a corrugated filler 11 and facing sheets of cardboard, the inner of which is generally designated by the numeral 12 and the outer of which is generally designated by the numeral 13. The unit of paper board is chosen of a length adapted to fit on a vertical corner of the article being shipped and the width is chosen in accordance with the number of ply and the size of corner desired. The unit of paper board shown is adapted to be scored and slit and then folded as shown in Figure 1. While the structure of Figure 2 may be scored and slit or sectionalized in any suitable manner as by hand, we preferably utilize a machine known, in the art to which this invention applies, as a slitting and scoring machine. While a slitting and scoring machine employing circular saw type knives for the slitting operation may be used and may be preferable for slitting some materials, we preferably use a slitting and scoring machine of the type generally illustrated in Figure 16. Preferably the corrugated paper board, whether consisting of single, double or triple wall corrugated paper board is scored and slit in a direction perpendicular to the corrugations.

The slitting and scoring machine illustrated in

Figure 16, while the details thereof have not been shown, in general comprises side stands 14 and 16 between which a rod or pair of rods 17 extend for retaining the side stands in upright position. A plurality of shafts 18, 19, 21 and 22 are journaled in the side stands and carry the scoring and slitting devices. The shafts extend through the side stands at one end and have mounted on the ends thereof pulleys 23 which may be driven from any suitable source of power. On the shaft 22 are mounted a plurality of cutting knives 24 each of which is adjustably secured to the shaft by means of a set screw 26. On the shaft 19 which lies immediately beneath the shaft 22 are mounted a plurality of anvils 27 which are similarly adjustably secured on the shaft by means of set screws 28. The shaft 21 lies in the same horizontal plane as the shaft 22 and has mounted thereon a plurality of anvils 29 which are similar to the anvils 27 and similarly adjustable along the shaft 21 upon which they are mounted. The shaft 18 is mounted in the same vertical plane as the shaft 21 and in the same horizontal plane as the shaft 19 and has mounted thereon a plurality of cutting knives 31 which are also adjustably secured to the shaft 18. Also mounted on the shaft 18 is a scoring knife 32. Each of the knives 24 and 31 and the scoring knife 32 is in spaced relationship with one of the anvils 27 and 29.

The sheet of corrugated paper is received between the cutting knives and the anvils to score and slit the paper board on opposite sides simultaneously. A complete pad unit used to form an entire side corner of the skeleton padding is passed through the machine in one piece so as to score and slit the paper board at all the desired points at the same time so that when the pad unit leaves the slitting and scoring machine it is ready for folding. For example, the corrugated paper board of Figure 2, in the unscored and unslit condition, is reversed from the position shown to bring the facing 13 uppermost and then fed into the machine. The scoring knife 32 forms scoring 34 in the paper board while the knives 24 form the slits 36 on the facing sheet 13 and the knives 31 form the slits 37 on the facing sheet 12. The knives and anvils of the machine of Figure 16 are spaced apart a distance sufficient to cut through one facing sheet and the corrugated sheet 11 but not through both facing sheets so that the complete corner pad unit of Figure 2 comprises a plurality of unsevered sections 38, 39, 40, 41, 42, 43, 44 and 45 which are adapted to be folded together to form the structure shown in Figure 1.

The various sections of the corner pad unit are of several widths in order that the center of the corner, at the point indicated by the numeral 47, when the pad unit is in the folded condition, is completely filled with material. The variable spacing is, of course, accomplished by setting the knives and anvils of the machine shown in Figure 16 at the desired spacing to produce the incisions 36 and 37 at the desired points. For example, the sections 42 and 43 are preferably made the same in width while the section 44 which is folded on the hinge formed by the incision 36 through 180° upon the section 43 is made slightly narrower. The decrease in width of the section 44 is equal to the thicknesses of one ply of single wall double faced corrugated paper board so that when the section 45, which is the same width as the section 44, is folded on its sectionalizing line 37 it will

enable the sections 42 and 43 to be folded with respect to each other at a true right angle joint. Similarly the sections 40 and 41 are made narrower than the width of section 42 by the thickness of three ply of single wall double faced corrugated paper board.

In folding the corner unit into the form shown in Figure 1 the unit is first folded on the scoring line 34 so that sections 42 and 43 are at an angle of approximately 90° to each other. The section 44 is then folded through 180° on to the section 43 and then the section 45 is folded in a reverse direction on to the section 44. The sections 39, 40 and 41 are folded in a similar manner upon the section 42. The section 38 is slightly less in width than the section 40 so that the section 38 which is contiguous to it may be folded at a 90° angle upon the face of the section 45 whereby an inner smooth joint 49 is formed which faces upon the article to be packed for shipment. If desired section 38 may be omitted in which case the section 39 is made of the same width as the section 40. However, this construction has the disadvantage of leaving an open joint at 49 and makes the number of ply on opposite sides of the corner unequal. It will be observed from Figure 1 that a complete, solid corner protective pad structure is formed which is unsevered throughout its length and may be used in a container without the necessity of pasting the various sections together. While we have shown the sections 42 and 43 between which the scoring line 34 is made as forming the outside of the corner, it will of course be appreciated that by reversing the slits or incisions 36 and 37 the pad may be reversely folded so that the scoring line 34 lies on the inside of the corner.

In Figure 3 we have illustrated a modified form of the construction shown in Figure 2 in which the sections 40', 41', 42', 43', 44' and 45' correspond respectively to the sections 40, 41, 42, 43, 44 and 45 of Figure 2. Two sections 51 and 52 are added on to the end of section 45'. These sections are made less in width than the width of section 43' by the thickness of three ply of single wall double faced corrugated paper board. Similarly four sections, 53, 54, 55 and 56, are added to the end of section 40'. These sections are narrower than the width of section 42' by the thickness of five ply of single wall double faced corrugated paper board. When cut in the manner described above the complete protective corner pad may be folded into the form shown in Figure 3 whereby a right angle joint will be formed. It will be noted that sections 52 and 56 do not form a continuous joint at the point 57, however, this construction is optional as by making sections 55 and 56 slightly narrower, the section 56 may be folded back on the section 52 to lie against the face thereof and form a closed joint similar to the joint 49 of Figure 1.

It will be apparent from Figures 1 and 3 that a protective corner pad may be built up having any desired number of ply or a different number of ply on each side of the corner. For example, as shown in Figure 1, there are four ply of single wall double faced corrugated paper board on each side of the corner, while in Figure 3, one side of the corner has seven and the other side five thicknesses of single wall double faced corrugated paper board. Thus a protective corner pad can be built up by properly determining the widths of the various sections so that any odd or even number of ply will lie on one side of

the corner and any odd or even number of ply will lie on the other side of the corner. The protective corner pad may therefore be varied to conform to the type of article being shipped and with relation to its fragility.

In Figures 4 and 5 we have illustrated a protective corner pad construction which is made out of double wall corrugated paper board in a similar manner to that described in connection with the single wall double faced corrugated paper board. The essential difference in the construction lies in the fact that two outer facing sheets 59 and 60 are used and two corrugated filler sheets 61 and 62 separated by an inner sheet 63. The complete corner unit is scored and sectionalized as shown in Figure 4 by the machine shown in Figure 16. It will be appreciated that the spacing of the sectionalizing lines must be changed from that described above so that the corner pad structure can be folded as shown in Figure 5. By properly scoring and sectionalizing the double wall corrugated paper board scoring 64 and incisions 65, 66 and 67 are formed which enable the pad unit to be folded as shown in Figure 5.

In Figure 6 we have illustrated still another modification of the structure illustrated in Figure 1 in which the protective corner pad is made up of triple wall corrugated paper board which is scored and sectionalized with the required spacing by the machine shown in Figure 16 into sections 68, 69, 70, 71, 72 and 73, thus forming a corner pad structure which has 9 ply of corrugated paper board on each side of the corner.

From the structures described and illustrated in Figures 1 to 6 inclusive it will be observed that a protective corner pad of any desired length and having any desired number of ply of corrugated paper board material may be built up and that when in completely folded condition the protective pad may be used to form a leg 75 of the protective skeleton padding illustrated in Figures 7 and 8.

In Figures 9 to 14 inclusive we have illustrated the manner of making the top 76 or bottom 77 protective corner pads shown in assembled form in Figures 7 and 8. In forming the top and bottom corner pad units a piece of single wall double faced corrugated paper board is chosen of a length (for clarity, the length of the paper board is indicated by the arrow A in Figure 10) sufficient to extend, when in folded condition, completely around the perimeter of the top of the article to be packed for shipment. The unit of single wall double faced corrugated paper board, shown in Figure 10, is scored at 78 and sectionalized at 79, 80, 81, 82, 83 and 84 on alternate sides of the unit, by the machine shown in Figure 16, forming pad sections 85, 86, 87, 88, 89, 90, 91 and 92. The unit of corrugated paper board of Figure 10 is then folded into the condition shown in Figure 11 by laying the pad sections 87 and 88 flatwise and then folding section 86 upon section 87 and folding section 85 upon section 86. The sections 89 and 90 are made of a width such as to leave, when folded as shown in Figure 11, a square opening 93 of a width equal to two thicknesses of single wall double faced corrugated paper board.

Section 91 is made of the same width as the sections 89 and 90 while the section 92 extends across the square opening 93 and is also made the same width as the sections 89 and 90 so that it terminates, as shown, a distance from the edge of section 85 equal to two thicknesses of single

wall double faced corrugated paper board. After the protective pad unit of Figure 10 has been folded into the condition shown in Figure 11 it is placed in the machine shown in Figure 17 5 where it is mitred as indicated at 94 and scored as indicated at 95.

The machine shown in Figure 17 comprises side stands 98 and 99 and a head 101. The head 101 has formed on the ends thereof slides 102 which are slidable in guides 103 formed in the side stands. The slides 102 are reciprocated in the guideways 103 in any suitable manner, for example by the mechanism indicated in the drawings. A pitman 104, secured to the guide 15 102, is eccentrically secured to a rotatable geared driving member 105 which is rotated by means of a gear 106 which may be driven from any suitable source of power.

The head 101 has a longitudinal slot 108 formed 20 therein along which is slidably secured a plurality of male dies 109. The dies 109 may be held in the slots by means of bolts 110 which permit the adjustability of the dies 109 along the head to vary the spacing between them. Beneath the head 101 and extending between the side stands 98 and 99 are a pair of cross members 111 and 112 having slots 113 for accommodating bolts 114 which are used to secure female die members 116 adjustably on the cross members 111 and 112. 25 Each of the male die members 109 has a scoring arm 117 extending therefrom and each of the female die members has a scoring groove 118 whereby the pad unit shown in Figure 11 may be placed in the machine and mitred as at 30 94, and scored as at 95 simultaneously. The machine shown in Figure 17 is set up to mitre and score the pad unit at four places simultaneously to form the four corners of the top or bottom corner pad sections out of one unit of paper board. It will, of course, be appreciated that the mitred joint 94 and the scoring 95 enables the pad unit to be folded so as to form the corners 121 of the top or bottom members 76 and 77. It will also be appreciated that the die members 35 are spaced between the side stands of the machine the distance apart required for properly spacing the corners 121 to accommodate the perimeter of the top or bottom of the article to be packed.

After the structure shown in Figure 11 has 40 been mitred and scored as indicated at 94 and 95 it is folded on each of the scoring lines 95, so that the four sides of the top or bottom corner pad units are formed. One corner in this 45 folded condition is shown in Figure 12. The structure is then folded from the condition shown in Figure 12 to the condition shown in Figure 13 by folding the sections 91 along the sectionalizing line 84 on opposite sides of the scoring 95 50 to a position at right angles to pad sections 92. Folding the pad unit from the condition shown in Figure 12 to the condition shown in Figure 13 causes the sections 91 and 92 to move with respect to the sections 85 and the sections 85, 86 55 and 87 to be folded at right angles to the section 88 along the scoring line 78 whereby the space 83 is completely filled and the edges of the sections 82 are brought flush with the edges of the sections 85, 86 and 87. In the position shown in Figure 13 the mitred joints 94, four in number 60 in a complete top or bottom pad unit, fit together and make a complete square cornered structure. After the pad unit has been folded with its corners as indicated in Figure 13 the complete top 65 or bottom pad unit may be held together by

pasting strips of paper over the joint 121. Also if desired paper may be pasted over the mitred joints to hold the assembly more rigidly in position.

In Figures 14 and 15 we have illustrated a 5 modified form of the construction illustrated in Figures 9 to 13 inclusive. The pad of Figure 15 which is a view similar to that of Figure 10 is scored at 124 and sectionalized at 126, 127, 128, 129, 130 and 131 by means of the machine shown 10 in Figure 16. After being folded into a condition similar to that illustrated in Figure 11 it is mitred and scored as illustrated in Figure 11 by means of the machine shown in Figure 17, after which it is folded into a condition similar to that illustrated in Figure 12. Figure 14 is a view similar 15 to Figure 9 which is taken on the line 9-9 of Figure 8. The advantage of the construction shown in Figure 14 lies in the fact that the number of ply on the top half 134 of the corner is 20 decreased to three, from that shown in Figure 9, and the number of ply on the bottom half, 135 of the corner is increased to five, from that shown in Figure 9, thus enabling the top or bottom corner pad structures to be made up of a varying 25 number of ply. In this manner the number of ply in the portions of the protective pad extending on the top of the article may be increased or decreased in accordance with the protective needs of the article to be shipped. It will of course be appreciated that double wall or triple wall corrugated board may also be used for forming the top or bottom units of the skeleton padding.

After the leg pads 75 and the top and bottom 30 pad units 76 and 77 of the skeleton protective padding have been completely formed, they may be secured around the object to be shipped by placing the leg pads at the vertical corners of, for example, a refrigerator, and the top and bottom pad units 76 and 77 at the top and bottom 35 of the refrigerator respectively after which, by means of adhesive paper the leg pads may be secured to the top and bottom pad units to form a complete skeleton padding extending around the refrigerator. The entire unit, with the skeleton padding, may then be slipped into a packing case 133 made of paper board or wood. While the skeleton padding may be secured in position on the article to be shipped as described 40 above, with most articles to be shipped it is found preferable to place the bottom pad unit 77 in position on the bottom of the container 133 and then place the leg pads 75 in position or else place the object to be shipped in the container 45 and then wedge the leg pads into place. After the article to be shipped is in position in the container the cover pad 16 may be placed over the top thereof. In this manner of assembling the container the legs 75 are, of course, unsecured to the top and bottom sections 76 and 77. This is, however, unnecessary as the leg pads are securely held in place by the outer walls of the container 133. When shipping certain types 50 of articles either a bottom section or a top section, or perhaps both, may not be required, in which case either or both may be omitted and only the leg pads 75 used.

The protective corner pads of our invention 55 may be slit and scored by the manufacturer thereof and shipped in a flat, unfolded condition to the manufacturer of the article to be packed for shipment or, if desired, the pads may be folded and pasted to retain their desired angular condition and shipped to the manufac- 60 65 70 75 80 85 90 95

turer of the article to be packed for shipment ready for insertion in the enclosing container.

It is believed that the method of making our protective skeleton pad structure is sufficiently clear from the foregoing description and it will be apparent that we have provided a simple and improved shipping container, the protective skeleton pad structure of which may be quickly and easily cut and assembled in the proper form and easily placed in the container in which the refrigerator or other device is packed. It will also be observed that we have provided a simple and economically manufactured protective corner pad construction which has a certain amount of resiliency and yet which will be sufficiently rigid as to properly space the article to be shipped and maintain it free from the side walls of the container. And, further, that various modifications and changes may be made in the details of the construction illustrated and the method of manufacture thereof without departing from the spirit of the invention as set forth in the appended claims.

We claim:

- 25 1. A method of forming a protective padding for use in a shipping container for the top or bottom of an article to be shipped which comprises sectionalizing without severing a unitary paper board element, folding the paper board element on the sectionalizing lines to form a padding unit having a plurality of ply of paper board, mitering one edge of the paper board element to form corners, and folding the paper board element so as to bring the mitered edges together to form a rectangular, angular top padding structure.
- 40 2. A method of forming a protective padding for use in a shipping container for the top or bottom of the article to be shipped which comprises sectionalizing without severing a unitary paper board element, folding the paper board element on the sectionalizing lines to form a padding unit having a plurality of ply of paper board, mitering the paper board element, scoring the paper board element on a line extending from the apex of the miter, folding the paper board element on said scoring, and again folding the paper board element to bring the mitered edges together.
- 55 3. A protective corner pad for use in a shipping container which comprises a unit of paper board having contiguous corner panels substantially fully joined together along a corner crease on the inner surface of said paper board, a partially severed panel adjoining one of said corner panels and attached thereto along an incision substantially parallel to said crease and extending through only most of the thickness of the paper board from the outer surface thereof to a depth sufficient to enable said partially severed panel to be readily folded along said incision through 180 degrees flat against the inner surface of its adjacent corner panel and remain in such folded position, and said partially severed panel being of such width as to abut against the inner surface of the opposite corner panel and form a square butt joint when said partially severed panel is folded flat against its corner panel and the two corner panels are folded toward each other about said crease so that their inner surfaces are facing and substantially perpendicular to one another.
- 70 4. A protective corner pad for use in a shipping container which comprises a unit of paper board having contiguous corner panels substan-

tially fully joined together along a corner crease on the inner surface of said paper board, two partially severed panels each adjoining one of said corner panels and attached thereto along an incision substantially parallel to said crease and extending through only most of the thickness of the paper board from the outer surface thereof to a depth sufficient to enable said partially severed panel to be readily folded along said incision through 180 degrees flat against the inner surface of its adjacent corner panel and remain in such folded position, one of said partially severed panels being of such width as to abut against the inner surface of the opposite corner panel and form a square butt joint when said partially severed panels are folded flat against their respective corner panels and the two corner panels are folded toward each other about said crease so that their inner surfaces are facing and substantially perpendicular to one another, and the second of said partially severed panels being sufficiently narrower than the first so as to permit the latter panel to pass the end of the former panel and form said joint.

5. A protective corner pad for use in a shipping container which comprises a unit of paper board having contiguous corner panels substantially fully joined together along a corner crease on the inner surface of said paper board, and a plurality of incisions substantially parallel to said crease and extending through only most of the thickness of the paper board and defining partially severed panels capable of being readily folded along said incisions through 180 degrees flat against the adjoining panel and remaining in such folded position, the incision next to said crease extending into the paper board from the outer surface thereof and alternate incisions on the same side of said fold line extending into the paper board from opposite surfaces thereof, and said partially severed panels being of such width that when they are folded flat against their adjoining panels and the two corner panels are folded toward each other about said crease so that their inner surfaces are facing and substantially perpendicular to one another, the edges of said partially severed panels will abut against the faces of other panels and form a square butt joint.

6. A protective corner pad for use in a shipping container which comprises a unit of paper board having contiguous corner panels substantially fully joined together along a corner crease on the inner surface of said paper board, two partially severed panels each adjoining one of said corner panels and attached thereto along an incision substantially parallel to said crease and extending through only most of the thickness of the paper board from the outer surface thereof to a depth sufficient to enable said partially severed panel to be readily folded along said incision through 180 degrees flat against the inner surface of its adjacent corner panel and remain in such folded position, and each of said partially severed panels being sufficiently narrower than its adjacent corner panel so as to permit the two corner panels to be folded toward each other about said crease so that their inner surfaces are facing and substantially perpendicular to one another when said partially severed panels are folded flat against their respective corner panels.
